CLAIM

The ornamental design for a pink bird plush with bow, as shown and described.

DESCRIPTION

FIG. 1 is a front left perspective view of a first embodiment of a pink bird plush with bow showing our new design; FIG. 2 is a front elevation view of the first embodiment thereof;

FIG. 3 is a rear elevation view of the first embodiment thereof;

FIG. 4 is a left side elevation view of the first embodiment thereof;

FIG. 5 is a right side elevation view of the first embodiment thereof;

FIG. 6 is a top plan view of the first embodiment thereof;

FIG. 7 is a bottom view of the first embodiment thereof;

FIG. 8 is a front left perspective view of a second embodiment of a pink bird plush with bow showing our new design;

FIG. 9 is a front elevation view of the second embodiment thereof;

FIG. 10 is a rear elevation view of the second embodiment thereof;

FIG. 11 is a left side elevation view of the second embodiment thereof;

FIG. 12 is a right side elevation view of the second embodiment thereof;

FIG. 13 is a top plan view of the second embodiment thereof; and,

bird plush with bow demonstrate a plush appearance. Any differences in the length or amount of the short lines of uneven length between portions of the pink bird plush with bow are not intended to indicate differences in plush level. The drawing is lined for color. More particularly, the portions having the vertical lines indicate portions of a first color, wherein the utilization of the vertical lines correspond to the USPTO convention for denoting pink.
